GODEFRIDUS HENDRIKUS CLERKX VAN KEULEN, OF APELDOORN, NETHERLANDS.

STEAM-PUMP.

1,356,241.

Specification of Letters Patent. Patented Oct. 19, 1920.

Application filed May 28, 1919. Serial No. 300,247.

To all whom it may concern:

Be it known that I, GODEFRIDUS HENDRIKUS CLERKX VAN KEULEN, engineer, a subject of the Queen of the Netherlands, 5 and residing at Apeldoorn, Loolaan 5, Netherlands, have invented certain new and useful Improvements in Steam-Pumps, of which the following is a specification.

This invention relates to improvements in 10 steam pumps and particularly to such pumps which operate without a flywheel; a principal object of the present invention being to provide an improved operating connection between the steam and pump pistons, as I 15 will hereinafter describe and point out in the appended claims.

In order that my invention may be better understood I will state that the constant resistance the piston or plunger of pumping 20 engines meets with necessitates a constant pressure on the steam piston in case no flywheel is used or such other device, which accumulates power during the first part of the stroke and delivers it during the second 25 part of the stroke, during which the steam expands.

Efforts have already been made to enable the application of expansion of the steam in 30 steam pumps operating without the aid of flywheel or any other like device. To this end namely the steam piston and the pump piston are connected by a system of rods, that in the beginning accelerates the motion of the steam piston and finally transmits it 35 retarded on the pump piston.

In the accompanying drawings forming part of this specification and in which like reference characters indicate like parts in the several views;

40 Figure 1 is a side elevation of a steam pump embodying my invention.

Fig. 2 is a side elevation in section of the sleeve and coöperating parts.

Referring to the drawing, *a* is the steam 45 cylinder and *b* the pump cylinder; *c* is the steam piston rod and *d* the pump piston rod, arranged in alinement but independent of each other. The ends of the two piston rods are oppositely threaded and engage the 50 sleeve *e*, which is tapped at its opposite ends to receive the oppositely threaded piston rods. The sleeve affords a rigid driving connection between the piston rods; but is so operatively associated with the coöperating 55 guide *i* that a flexible operation is attained.

To secure the operation just mentioned

the sleeve *e* is provided with a pin *f* projecting outwardly and working in a slot in the guide *i*. This slot is shaped in a predetermined manner to afford a complete circuit, 60 and for the sake of clarity I have here illustrated it as entirely cut through the wall of the guide, though it may of course be formed merely upon its inner face. In the form illustrated wherein the slot is cut entirely 65 through the wall of the guide, two sleeves *s* are secured by welding or otherwise to the exterior of the guide on both sides of the slot, for the purpose of supporting that portion of the guide which the slot encircles. The portion *g* of the slot is straight, merging toward its right hand end into a spiral which opens into a return straight reach *h* which merges into a spiral communicating at its opposite end with the straight 70 reach *g*. The guide *i* has also a rectilinear slot *k* which is engaged by a cross pin *l* on the pump piston rod *d*, which prevents the latter from twisting. The steam piston rod *c* is prevented from turning by the lever *m* 80 pivoted thereto and serving to operate the steam valve.

The valve forms no part of my invention in itself, and is not shown in detail, but is operated by the rod *p* connected at one end 85 of the rock lever *m* and at its opposite end to the valve lever *r*. A steam cut-off valve is operated by the rod *n* connected to the piston rod of the coöperating steam cylinder (not shown), the pump being of the 90 duplex type.

The operation of the present device is as follows:—When the steam piston is at the end of its return stroke the parts are in the position shown in the drawing. Upon the admission of steam behind the piston in the cylinder *a* the rod *c* moves to the right driving with it the sleeve *e* and consequently the pump piston *d*. During this initial portion 95 of the stroke the parts move in unison. As soon, however, as the pin *f* on the sleeve reaches the spiral portion of the groove *g* in the stationary guide *i* the sleeve *e* is rotated on the piston rods, thus drawing the two rods toward each other while they nevertheless travel in the same direction, but the steam piston at greater speed than the pump piston. The length of the rectilinear portion of the slot *g* is predetermined with relation to the operation of the steam valve 100 so that the steam is cut off from the cylinder *a* substantially simultaneously with the 105

entry of the pin *f* into the spiral portion of the slot. Thus, the initial travel of the pistons is secured under full head of steam, while the latter portion of the stroke at 5 which they travel at reduced and varying speeds occurs during the expansion of the steam in the piston cylinder.

At the completion of the stroke the pin *f* on the sleeve *e* has reached the end of the 10 spiral portion of the slot *g*. The steam is now admitted to the opposite side of the piston in the cylinder *a*, and the piston is driven to the left carrying the pin *f* on the sleeve *e* first through the rectilinear portion 15 of the slot *h* and then through the spiral portion of the slot, thus returning the parts to the position shown in the figure. During the latter portion of the return stroke the rotation of the sleeve *e* has the effect of retarding the return of the pump piston. 20

Various modifications in detail will readily occur to those skilled in the art which do not depart from what I claim as my invention.

25 I claim—

1. A steam pump comprising a steam cylinder, a pump cylinder, independent pistons and piston rods for the steam and pump cylinders respectively, the piston rods 30 being arranged in alinement and oppositely threaded at their free ends, in combination with a sleeve adapted to receive said rod ends and serving to form an operative connection between the same, in combination 35 with means associated with said sleeve for varying the strokes of said pistons relative to each other during their course.

2. A steam pump comprising a steam cylinder, a pump cylinder, independent pistons 40 and piston rods for the steam and pump cylinders respectively, the piston rods being arranged in alinement and oppositely threaded at their free ends, in combination with a sleeve adapted to receive said rod 45 ends and serving to form an operative con-

nection between the same, in combination with means associated with said sleeve for driving said pistons in unison during a portion of their strokes and varying their travel during the remainder of their course. 50

3. A steam pump comprising a steam cylinder, a pump cylinder, independent pistons and piston rods for the steam and pump cylinders respectively, the piston rods being arranged in alinement and oppositely threaded at their free ends, in combination 55 with a sleeve adapted to receive said rod ends and serving to form an operative connection between the same, in combination with means associated with the sleeve for 60 causing the same to rotate during the stroke of the pistons.

4. A steam pump comprising a steam cylinder, a pump cylinder, independent pistons and piston rods for the steam and pump 65 cylinders respectively, the piston rods being arranged in alinement and oppositely threaded at their free ends, in combination with a sleeve adapted to receive said rod 70 ends and serving to form an operative connection between the same, in combination with means for causing the sleeve to rotate during a portion of the stroke of said pistons.

5. A steam pump comprising a steam cylinder, a pump cylinder, independent pistons and piston rods for the steam and pump cylinders respectively, the piston rods being arranged in alinement and oppositely 75 threaded at their free ends, in combination with a sleeve adapted to receive said rod ends and serving to form an operative connection between the same, in combination 80 with a rigid member having a pin and slot connection with said sleeve causing the latter to rotate on the piston rod during a portion of the stroke.

In testimony whereof I affix my signature.

GODEFRIDUS HENDRIKUS

CLERKX VAN KEULEN.
